LIQUID DISPENSING CONTAINER

Forrest C. Garrison, Glencoe, Ill.

Application December 23, 1933, Serial No. 703,819

10 Claims. (Cl. 225—40)

This invention relates to liquid containers having delivery spouts which are adjustable to operative and inoperative positions and through their movement operate valves for controlling outward flow of liquid in the container. The construction has various uses but is herein disclosed as formed and dimensioned particularly for reception in domestic refrigerators.

A purpose of the invention is to provide a container of the class described with improvements permitting the drawing off of small portions of the liquid without allowing the remaining portion to become unnecessarily decarbonized, in the case of carbonated beverages, by the admission of more air than may be necessary to effect outward flow of the liquid. A further purpose of the invention is to provide for controlling the outward flow of the liquid with its vapor while under its own vapor pressure. Another purpose of the invention is to provide a head for the container which is so formed as to neatly receive a pivoted, combined spout and valve operating element. Another object of the invention is to provide valves under the control of the swinging spout, which valves successively move to open, first to permit a flow of liquid if under pressure, and then to admit air to the container if necessary for allowing proper flow of liquid in case the liquid is not under the necessary pressure from weight and vapor or gas arising therefrom.

The objects of the invention are accomplished by means of a construction as illustrated, wherein:

35 Figure 1 is a longitudinal sectional view of the container as indicated by line 1—1 of Fig. 5.

Fig. 2 is a sectional view of the head of the container as indicated by the line 2—2 of Fig. 1.

40 Fig. 3 shows the combined delivery spout and valve operating handle in plan.

Fig. 4 is a side view of the spout and partly in section.

Fig. 5 is an end view of the spout end of the container which is shown partly broken away and partly in section.

Fig. 6 is a sectional view of the head of the container as indicated by the line 6—6 of Fig. 5.

Fig. 7 shows in detail an air inlet valve.

50 Fig. 8 shows in detail a valve for controlling the outward flow of liquid.

Fig. 9 is an end view of the valve shown in Fig. 8.

Fig. 10 is a sectional detail of a check valve for preventing the outward flow of vapor or liquid from the air inlet valve.

In its general features, the construction illustrated consists of an inner cylindrical container carried by an outer rectangular shell which is made in this form to prevent rolling. The closing head of the inner container carries pivoted thereto, on a horizontal axis, a combined spout and valve operating means, and is made concave on its outer surface to receive the spout folded against it in protected position when the valves operated by the spout are in closed position. When the spout is swung downwardly the valves remain closed until the spout moves through, or preferably below, its horizontal position when the liquid flow control valve first gradually opens, and if the flow is not fast enough, further depression of the spout results in opening an upper check controlled air intake valve. This valve also serves to release vapor, if under pressure, to the spout.

In the drawings, the outer rectangular shell 1 has rounded corners and fits a similarly formed head 2 for the inner cylindrical drawn metal container 3, which is separated from shell 1 by insulation 38. The shell is secured to the head by being crimped into depressions 4. The head 2 has an inner cylindrical flange 5 in threaded engagement with internal threads at the end of container 3. The head is dished inwardly as indicated at 6, and is a casting formed to receive a spout 7 pivoted therein. The head 2, container 3 and spout 7 may be made of some such material as aluminum magnesium alloys, which are believed not to have a detrimental effect on carbonated beverages such as draft beer.

The spout 7 is pivoted on a horizontal axis 35 in a boss 8 formed at the lower end of the head. The head also carries a spring pressed ball or plunger 9 for bearing against the lower end of the spout to make a tight sliding fit against the end of boss 8 at the shoulder 10 of the spout 40 (Fig. 3) at the inner end of its hollow pivot shank 11. The pressure of spring 12 bearing against ball 9 is regulated by screw 13. The head 2 is also provided with a filling plug 14 and a carrying handle 15 which spans the concave 45 portion of the head and is secured thereto by the screws 16.

The head is formed and cored out to provide passageways 17 and 18 respectively for liquid, and gas or vapor from the container to the spout. 50 Passageways are controlled by valves 19 and 20 and are held to their seats by springs 21 and 22. The valve springs are made of tempered aluminum magnesium alloy or other material plated or coated to prevent any detrimental effect on 55

the liquid, and the valve faces are made of a composition which is suitable for the purpose and properly seals the openings. The springs 21 and 22 have their ends 23 and 24 clipped into notches 5 25 and 26 in the head. The valve stems 27 and 28 are engaged at their ends by shoulders 29 and 30 formed on the shank 11 of spout 7. The lower end of the vent valve stem 28 has four small pressed up nubs 31 for fitting the hole 32 10 in the head. Otherwise both valves are kept in alinement with their seats by the springs 21 and 22.

The valve 19 controls the flow of liquid from the container through the hole 33 communicating with the spout. Valve 20, if opened, will allow gas or vapor under pressure to flow downwardly to the spout in case the spout is lowered far enough to open the valve, and when the spout is in this position and there is no pressure within 15 the container, air may flow inwardly past the valve 20 through openings 34 in the head 35 of a nipple 36. Outward spurting of gas through this nipple is prevented by check valve 37. During shipment, the spout is kept closed by a screw 20 cap 38 and is folded inwardly against the head, in which position the spout and the valves are seated.

In the use of the construction it is first steam cleaned through the filler plug opening. It is 30 then filled and the plug 14 is replaced. The spout is capped and folded against the head 2. The container is placed in a refrigerator with the head towards the front. Then to draw a portion of the liquid, the spout is swung downwardly to the horizontal position, or rather, 35 slightly further as indicated by the broken lines 1' (Fig. 1), in which position valve 19 is held open by the shoulder 29 engaging the end of the valve stem. The liquid then flows through the spout under its own pressure, but if the liquid 40 is well cooled the flow will slow up and the spout is further depressed until it reaches an angle of about 20° below the horizontal as indicated by the broken lines 1'' (Fig. 1), which is sufficient 45 to open the upper valve 20 and allow the necessary inflow of air to the container to continue the pressure required for further outward flow of the liquid. If the spout is depressed to its lowermost position while there is still vapor 50 pressure within the container, both the upper and lower valves permit outward flow to the spout. Under such circumstances the check 37 (Fig. 10) prevents outward spurting through the air inlets 34.

55 Although but one specific embodiment of this invention is herein shown and described, it is to be understood that details of the construction shown may be altered or omitted without departing from this invention as defined by the 60 following claims:

I claim:

1. A liquid dispensing container having a head, a spout pivoted to the head, said head having 65 two passageways respectively leading from the top and bottom of the container to the inner end of the spout, and a valve in each of said passageways under the control of said pivoted spout.

2. A liquid dispensing container having a head, a spout pivoted to the head, said head having 70 two passageways respectively leading from the top and bottom of the container to the inner end

of the spout, a valve in each of said passageways under the control of said pivoted spout, and connections between said spout and valves for successively operating the valves upon a swinging motion of the spout. 5

3. A liquid dispensing container having a head, a spout pivoted to the head, said head having two passageways respectively leading from the top and bottom of the container to the inner end of the spout, a valve in each of said passageways under the control of said pivoted spout, and an air intake means communicating with one of 10 said valves.

4. A liquid dispensing container having a head, a spout pivoted to the head, said head having two 15 passageways respectively leading from the top and bottom of the container to the inner end of the spout, a valve in each of said passageways under the control of said pivoted spout, and an air intake means communicating with one of 20 said valves, and provided with a check valve.

5. A liquid dispensing container having a head provided with a spout, said head having two passageways respectively leading from the top and bottom of the container to the inner end of the 25 spout, each of said passageways having a valve, operating means for said valves, and an air intake means communicating with one of said valves.

6. A liquid dispensing container having a head 30 provided with a spout, said head having two passageways respectively leading from the top and bottom of the container to the inner end of the spout, each of said passageways having a valve, operating means for said valves, an air intake 35 means communicating with one of said valves, and a check valve in said air intake means.

7. A liquid dispensing container having a head provided with a spout, said head having two passageways respectively leading from the top and 40 bottom of the container to the inner end of the spout, each of said passageways having a valve, means for successively operating said valves, and an air intake means communicating with one of 45 said valves.

8. A liquid dispensing container having a head provided with a spout, said head having two passageways respectively leading from the top and bottom of the container to the inner end of the spout, each of said passageways having a valve, 50 means for successively operating said valves, an air intake means communicating with one of said valves, and a check valve in said air intake means.

9. A liquid dispensing container having a liquid 55 dispensing valve near the bottom thereof, and an upper air intake valve, a delivery spout for communicating with said dispensing valve and pivotally mounted on said container, said delivery spout having connections with said valves for operating the valves when the spout is swung on its pivot.

10. A liquid dispensing container having a liquid 65 dispensing valve near the bottom thereof, and an upper air intake valve, a delivery spout for communicating with said dispensing valve and pivotally mounted on said container, said delivery spout having connection with said valves for operating the valves successively when the spout is 70 swung on its pivot.

FORREST C. GARRISON.
